(57) CLAIM

The ornamental design for a bristle arrangement for a toothbrush as shown and described.

DESCRIPTION

FIG. 1 is a perspective view of the bristle arrangement for a toothbrush showing the new design;

FIG. 2 is a front view thereof; and,

FIG. 3 is a right-side view thereof.

The broken lines illustrating bristles illustrate portions of the article, and form no part of the claimed design. The broken lines illustrating a head of a toothbrush illustrates environment, and form no part of the claimed design.

1 Claim, 1 Drawing Sheet
